UNITED STATES PATENT OFFICE.

OTTO BOTT, OF OSHKOSH, NEBRASKA.

WINDMILL.

Application filed January 30, 1923. Serial No. 615,807.

To all whom it may concern:

Be it known that I, Otto Bott, a citizen of the United States, residing at Oshkosh, county of Garden and State of Nebraska, have invented certain new and useful Improvements in Windmills; and I do declare the following to be a full, clear, and exact description of the invention, such as will enable others skilled in the art to which it appertains to make and use the same, reference being had to the accompanying drawings, and to the characters of reference marked thereon, which form a part of this specification.

13 This invention relates to windmills of the type employed for pumping water.

It is the object of this invention to produce a new and improved type of windmill which shall not be so liable to be injured by 20 wind storms, and which shall be of simple and substantial construction.

In order to describe my invention so that the same may be clearly understood, I shall have reference to the accompanying drawing, in which:

Fig. 1 is a side elevation of the improved mechanism of my windmill with a small portion thereof broken away.

Fig. 2 is a top plan view of my windmill 30 showing the parts in neutral position, parts thereof being broken away to better show the construction.

Fig. 3 is a section taken on line 3—3, Fig. 1.

Fig. 4 is a view similar to that in Fig. 2, but showing the parts in operative position.

Fig. 5 is a section taken on line 5—5, Fig. 1; and

Figs. 6 and 7 are sections taken on line 40 6—6, Fig. 4 and shows two successive positions of the means for throwing the mechanism into operative position.

The same reference numbers will be used to designate the same parts throughout the 45 several views.

Numeral 1 represents the upper part of the supporting tower upon which my windmill rests and which has on its upper surface a raceway 2 for the reception of balls 3 upon 50 which the turntable 4 rests. On one side of the center the turntable is provided with a U-shaped bracket 5 between which is journaled an arm 6. The arm 6 has a transverse

hub 7. A shaft 8, indicated by dotted lines in Fig. 1, extends through the hub 7 and 55 through the two parallel sides of the U-shaped bracket 5, the upper surface of which has a hub 9 which extends upwardly for a short distance. Secured to the upper end of shaft 8 is a bevel gear 10, the purpose of which will appear as the description proceeds. The arm 6 has its outer end bifurcated, and between the two parallel arms 11 and 12 is pivotally mounted a sail which consists of two rectangular members 13 and 14, having one end connected to form the vertex of a dihedral angle. The members 13 and 14 are separated by brackets 15 in the manner shown in Fig. 5. A shaft 16, 60 passing through central openings provided therefor in the brackets 15, extends through suitable bearings near the ends of arms 11 and 12 and serves as the pivot about which the sail turns. An arm 17 is now rotatably mounted on shaft 16 and has its end connected by means of springs 18 with the ends of brackets 19 which in turn are held in adjusted position by means of rods 20. The springs 18 are so tensioned that the arm 17 65 will normally bisect the angle between the sides 13 and 14. To the upper end of shaft 16, I secure a bevel gear 21. Mounted in a suitable manner on the upper ends of shafts 8 and 16 are bearings 22 and 23 respectively, which support the shaft 24 in the manner 70 shown most clearly in Fig. 1. Shaft 24 has collars 25 on one side of bearings 22 and 23 and on the other side gear wheels 26 and 27 which engage respectively the gears 10 and 21. A metal plate or platform 28 is supported from the turntable by suitable means, such as rods 29^a, and serves as the support 75 for a system of bell cranks and connecting rods, which is shown in Figs. 2 and 4, and which will now be described.

Pivoted to the upper side of the platform 28 are two bell cranks 29 and 30. One arm of crank 29 is connected by means of a rod 31 with the gear wheel 10 in such a manner that any movement of the bell crank will 80 rotate the gear. A connecting rod 32 joins the parallel arms of the cranks 29 and 30 so that any movement of the one will be transmitted to the other. A slotted bar 33 is pivotally connected to the end of one arm 85 of the bell crank 30 and has its other end 90

95

100

105

slidably mounted in the bracket 34. The central portion of bar 33 has a long narrow slot through which the shaft 24 passes. When the arm 6 is oscillated about its pivot 5 the shaft 24, which is connected to the arm 6, will also oscillate. The length of the slot in bar 33 is such that when the arm 6 and shaft 24 oscillate, the shaft will strike against the ends of the slot and move the bar 33 first in one direction and then the other. Thus, when arm 6 and shaft 24 have moved in a counter-clockwise direction to the extent shown in Fig. 4, the bar 33 will have been moved upwardly and by its movement rotated the bell cranks and the gears 10. Springs 35 are connected to the lever arms in such a manner that when the latter occupy their extreme positions in either direction, the tension of the springs will serve 10 to prevent reverse movement until the shaft 24 strikes the opposite end of the slot and exerts sufficient force to overcome the tension of the springs and move the bell cranks and associated parts to the opposite position 15 20 25 from that shown in Fig. 4.

Let us now explain the purpose and the function of gears 10, 26 and 27, 21 and shaft 24. If we suppose that the parts occupy the position shown in Fig. 4 and that 30 the wind blows in the direction of the arrows A, the reaction of the wind, as it strikes the sides of the plate 14, will produce a resultant force that will tend to move the arm 6 and attached parts in a clockwise direction. The gear 10 is held from rotation by rod 31 and the action of the springs 35. As a result of this, the gears 26 will 35 be forced to rotate and this in turn will rotate the shaft 24, gears 27, 21 and shaft 40 16, and since the sail is connected to the shaft 16 by means of springs 18, the angle of the sail, with respect to the arm 6 will gradually change as the arm moves. The parts are so proportioned that the 45 angle that the sides of the sail makes, with respect to the wind, remains constant throughout the movement of the arm 6. When the arm has moved in a clockwise direction until shaft 24 strikes the other 50 end of the slot in arm 33, the arm will be forced to move and will oscillate the bell cranks and rotate the gear 10. As the gear 10 is rotated in a clockwise direction (Fig. 4) the sail will be oscillated about its shaft 55 16 to such an extent that side 13 will make with the wind the same angle as side 14 did when the parts were in the position shown by full lines in Fig. 4. The reaction between the wind and sail will now be such 60 that the resultant force will cause the parts to move backwardly into the position shown in Fig. 4, when the bell cranks will once more be oscillated and the parts set so as to cause a clockwise rotation of the arm 6 and this will continue indefinitely as long

as the wind is sufficiently strong to produce the required force.

In order to convert the oscillating movement of the arm 6 into a vertical reciprocating movement, by means of which a pump may be operated, the following mechanical movement is provided: Referring now more particularly to Fig. 3, the turntable 4 has a downwardly projecting tubular portion 36 which extends through a hole in the support 1. Through this opening a pump rod 37 extends downwardly to the pump. A lug 38 projects upwardly from the turntable 4 and serves as the fulcrum for the bell crank lever 39. The upper end of the pump rod is pivotally connected to the horizontal arm of the bell crank lever in the manner shown in Fig. 3. To the upper end of the vertical arm of the bell crank, I pivot a pitman 40 whose other end is provided with an opening which encloses the arm 6. As the arm 6 oscillates about its pivot 8, it rocks the lever arm 39 and reciprocates the pump rod 37.

In order to stop the operation of the windmill, I provide the following mechanism: The bell crank 30 is provided with two projections 41 and 42 which are adapted to be engaged by a cam 43. The cam is pivoted to the platform and is provided with a vane 44. A spring 45 tends to hold the vane and the cam in the position shown in Fig. 4 and may be moved to the position shown in Fig. 2 by a pull on the cord 46. When the cam 43 is in the position shown in Fig. 2, the sail is held in such a position that the wind exerts an equal force on each side, with the result that there is no tendency for arm 6 to move. The position shown in Fig. 2 is termed the neutral position. When the tension in cord 46 is released, the bell cranks are free to move, but since the sail is in neutral position, there is no tendency for the parts to oscillate. In order to start the windmill, it is necessary to move the parts from neutral position and this is accomplished by the following means: A bar 47 is slidably mounted in a guide 48 and carries at its end a hook 49, which is adapted to engage the side of lever 30. A pull on the rope 50 will move the mechanism to the position shown in Fig. 4 and permit the parts to function. A spring 51 holds the hook 49 retracted.

In case of a strong wind which would be liable to cause damage, to the mechanism, the vane 44 will be rotated and the cam 43 moved into neutral position, which will prevent the arm 6 from oscillating. The function of the springs 18 is to act as a governor or regulator, as they permit the sail to yield whenever the force becomes too great and thus reduce the value of the resultant force which produces the movement.

It is evident that I may make the sail of any suitable size and also that I may duplicate the parts without departing from the spirit of the invention. Although I have 5 described my mechanism as being adapted to be operated by wind power, it is evident that the same mechanism would operate in a current of water instead of air.

I am aware that many minor modifications can be made without departing from the spirit of the invention and the device shown and described is merely intended to show one possible embodiment of my invention. I therefore desire to obtain as 10 broad protection as the state of the art will permit and contemplate making any changes that may be required, and which fall within the scope of the appended 15 claims.

20 Having now described my invention, what I claim is:

1. In a device of the class described in combination; a turntable adapted to rotate about a vertical axis; a bracket secured to 25 said table; an arm pivoted to said bracket and adapted to oscillate about a vertical axis; a sail pivotally connected to the free end of said arm and adapted to be oscillated about a vertical axis so as to vary its angular 30 relation to the arm; means for altering the angular relation of the arm and the sail as the arm oscillates about its pivot; and means for reversing the angular relation of the arm and the sail at the end of each 35 oscillation of the arm.

2. In a mechanism of the class described; a support; a turn-table rotatably mounted thereon; a bracket secured to said support; an arm pivotally mounted on said bracket 40 so as to swing in a horizontal plane, the free end of said arm being bifurcated; a sail comprising two plates joined at one end and spaced at the other so as to form an acute dihedral angle, said sail being 45 pivotally mounted between the two arms of the free end of the arm so as to oscillate about a vertical axis; a gear secured to the said bracket; a second gear intermeshing therewith; a third gear secured to the shaft, 50 about which the sail oscillates; a fourth gear intermeshing with the third gear; a shaft connecting said second and fourth gears; a bell crank lever; a connecting rod between one arm of said lever and said first gear whereby the movement of the lever 55 will move the gear; resilient means for holding said lever in each of two extreme positions; and means comprising the said shaft for moving the lever from one extreme 60 position to the other.

3. A windmill comprising in combination a support; a turntable rotatably mounted thereon; a bracket on one side of said turntable; a vertical shaft secured to said bracket; an arm mounted on said shaft

and free to rotate thereabout, the free end of said arm being bifurcated; a sail pivotally mounted in said bifurcation, said sail normally occupying an angular position with respect to the arm; means for gradually altering the angular relation of the sail and arm as the latter moves about its pivot; and means for limiting the movement of the arm in either direction, said means comprising a system of levers and rods which cooperate with the means for shifting the sail. 70 75

4. A windmill comprising in combination a support; a turntable rotatably mounted thereon; a bracket on one side of said turntable; a vertical shaft secured to said bracket; an arm mounted on said shaft and free to rotate thereabout, the free end of said arm being bifurcated; a sail pivotally mounted in said bifurcation, said sail normally occupying an angular position with respect to the arm; means for gradually altering the angular relation of the sail and arm as the latter moves about its pivot; means for limiting the movement of the arm in either direction, said means comprising a system of levers and rods which cooperate with the means for shifting the sail; and means for moving said sail into parallel relation with said arm whereby the parts will assume inoperative position. 80 85 90 95

5. A windmill comprising in combination a support; a turntable rotatably mounted thereon; a bracket on one side of said turntable; a vertical shaft secured to said bracket; an arm mounted on said shaft and free to rotate thereabout, the free end of said arm being bifurcated; a sail pivotally mounted in said bifurcation, said sail normally occupying an angular position with respect to the arm; means for gradually altering the angular relation of the sail and arm as the latter moves about its pivot; means for limiting the movement of the arm in either direction, said means comprising a system of levers and rods which cooperate with the means for shifting the sail; means for moving said sail into parallel relation with said arm whereby the parts will assume inoperative position; and means for locking the parts in inoperative position. 100 105 110 115

6. A windmill comprising in combination a support; a turntable rotatably mounted thereon; a bracket on one side of said turntable; a vertical shaft secured to said bracket; an arm mounted on said shaft and free to rotate thereabout, the free end of said arm being bifurcated; a sail pivotally mounted in said bifurcation, said sail normally occupying an angular position with respect to the arm; means for gradually altering the angular relation of the sail and arm as the latter moves about its pivot; means for limiting the movement of the arm in either direction, said means comprising 120 125 130

a system of levers and rods which cooperate with the means for shifting the sail; means for moving said sail into parallel relation with said arm whereby the parts will assume an operative position; means for locking the parts in operative position; and means for moving the parts into operative position.

In testimony whereof I affix my signature, in presence of two witnesses.

OTTO BOTT.
